F. PFEIFFER

CRACKING FURNACE

Filed May 1, 1922

FIG. 1

FIG. 2

INVENTOR
Frank Pfeifer
BY E.B. Birkenbeul
HIS ATTORNEY

UNITED STATES PATENT OFFICE.

FRANK PFEIFER, OF MINNEAPOLIS, MINNESOTA.

CRACKING FURNACE.

Application filed May 1, 1922. Serial No. 557,536.

To all whom it may concern:

Be it hereby known that I, FRANK PFEIFER, a citizen of the United States, and a resident of Minneapolis, in the county of 5 Hennepin and State of Minnesota, have invented a new and useful Cracking Furnace, of which the following is a specification.

This invention relates more particularly to furnaces for cracking or breaking down 10 vegetable matter and driving off by means of heat certain volatile compounds.

The object of my invention is to provide an exceedingly simple, cheap and efficient 15 furnace in which vegetable matter may be placed and subjected to heat until all desirable volatile matter has been driven off.

A further object is to so construct my furnace that the matter being treated will 20 itself act as a heat retainer, thereby eliminating the expensive insulation now required.

Another object is to so construct the furnace that the filling and cleansing of the retort and the stoking of the furnace may be 25 accomplished with a minimum expenditure of labor.

Still another object is to so construct the furnace that combustion of the heating material will be complete within the furnace, 30 thereby avoiding undue loss of heat by reducing the stack temperature.

I accomplish these results in the manner set forth in the following specification and illustrated in the accompanying drawing, in 35 which:

Figure 1 is a vertical section through the machine with a portion of the front not cut away to show a flap valve. Figure 2 is a front elevation with a portion cut away in 40 section along the line 2-2 in Fig. 1.

Similar numbers of reference refer to the same or similar parts throughout the views.

Referring in detail to the drawing, I have 45 constructed my furnace of a curved shell 10 having the straight sides 11 which extend to the floor line. A back 12 is welded along the flanged edge 13 to the shell 10. A front 14 is also welded along the flanged edge 15 to the shell 10. An angle iron arch 16 on 50 the inside of the shell 10 supports same midway between the ends 12 and 14.

The firing chamber is constructed of a smaller shell 17 inside of the larger shell 10. The straight sides 18 of the shell 17 turn 55 outwardly to form the floors 19 and then downwardly as walls 20 along the inside of

the side walls 11 to which they are secured. Angle irons 21 are secured to the lower and inner sides of the walls 20. A central dividing wall 22 extends from the floor line 60 to the under side of the floors 19 and up between the walls 18 and forms a baffle for the fire box. Angle irons 23 on the front 14 and the wall 22 support the grate bars 24 which fill the space between the walls 18 in 65 front of the wall 22.

The furnace fire is fed through the square chute 25 which projects from the front 14 and is provided with a flared edge 26 and has a fire door 27 hinged at the top and 70 opening inwardly when straw is pushed against same in stoking. Retort doors 28 are provided near the middle of the side walls and are preferably placed so that the vegetable carbon residue remaining in the 75 retort after a charge has been treated can easily be removed through the doors 28. It will be understood that the retort includes the space between the shells 10 and 17 and above the floors 19. 80

A retort charging door 29 is provided on the front 14. Rising from the rear of the shell 17 is a flue 30 which turns a right angle bend into the horizontal flue 31 which also bends squarely and upwardly to form the 85 flue 32 which projects above the top of the shell 10. A stack 33 which is of any suitable height depending upon local conditions is placed over the projecting top of the flue 32. A threaded coupling 34 is welded into 90 the shell 10 above the flue 30. A testing cock 35 and a flap check valve 36 are also provided on the front 14 and open into the retort. 95

The space below the floors 19 and behind the walls 32 may be filled with earth if desired. An ash pit door 37 is also provided.

The operation of my device is as follows: The space between the shells 10 and 17 and above the floors 19 is charged with straw, or 100 vegetable matter of any kind, and the doors 28 and 29 securely closed. A fire of straw or other material, or even gas produced by the furnace itself, is made over the grates 24 and maintained until gas ceases to generate. 105 This point can be ascertained by opening the test cock 35, the volatile matter being, of course, passed out of the coupling 34 from which it is carried to suitable condensers and washers and into a gasometer from 110 which it is drawn as required.

As the furnace cools the flap check valve

36 admits air to the retort and prevents the gas from being drawn back through the coupling 34 or the collapsing of the outer shell itself.

5 It has been found by experiment that the most inexpensive way to secure most complete combustion within the furnace and the resulting low stack temperature was to use the square turns in the smoke discharge flues 30, 31 and 32. It is evident that instead of passing directly out to the atmosphere the burning gases form into eddy currents at these points which delay their escape from the furnace, with very desirable results.

10 It is evident that these furnaces can be employed in batteries and that the manufactured gas itself can be used as a heating medium, as above stated, without departing 15 from the spirit of my invention.

I am aware that many kinds of furnaces are used for breaking down vegetable matter, I therefore do not claim same broadly but only intend that it shall cover those 20 forms and modifications which fall fairly within the appended claims.

25 What I claim as new is:

1. In a cracking furnace, the combination of a wagon top outer shell having an 30 internal combustion chamber extending its full length with a smoke flue leading from the rear of said combustion chamber out to the atmosphere through the forward end of said wagon top shell, a charging door at 35 the forward end of said shell above said combustion chamber, and cleanout doors in the sides of said wagon top shell.

2. In a cracking furnace, the combination of a wagon top outer shell with a similarly shaped combustion box supported 40 within said outer shell, said combustion chamber having its smoke flue at its rear top and leading forward and upward through the outer shell, the space between said shell 45 and above the bottom of the combustion chamber forming a retort, charging and cleanout doors for said retort, a baffle near the middle of said combustion chamber, grates in front of said baffle, a gas outlet 50 port for said retort, and a projecting fire door opening having hinged at its upper

side a self closing door adapted to be opened by pressure from the outside.

3. In a cracking furnace, the combination of a wagon top outer shell having a 55 raised floor, a combustion chamber extending the full length of said outer shell, a transverse dividing wall under the middle of said raised floor extending up into said combustion chamber in the form of a baffle, 60 grates in said combustion chamber in front of said baffle, a stoking chute in the front of said outer shell opening into said combustion chamber, a self-closing door in said stoking chute, a smoke flue having square 65 bends adapted to carry smoke from the rear of said combustion chamber to the front of said outer shell, and a check valve opening into the retort formed between the outer shell and the combustion chamber. 70

4. A cracking furnace having a relatively long firing compartment and having a baffle near its center and grates in front of said baffle, and having a retort formed over and along the sides of said firing compartment, and flue means for carrying burned gases from said firing compartment through said retort and out to the atmosphere. 75

5. In a cracking furnace, the combination of a pair of side walls joined by a rounded top and having end walls at both ends of said side walls, with an internal firing compartment consisting of a pair of side walls united by a round top said side walls being turned outwardly at their feet and downwardly against the inside of said outer walls, said firing compartment members being joined at their ends to the front and rear end walls, a transverse baffle wall 80 near the middle of said frame extending from the floor line to well up into the firing compartment grates in front of said baffle, a stoking chute in the front wall over said 85 grates, a square angled return flue from the rear top of said firing compartment to the front of said rounded top, a port for the escape of generated gas, a charging door over the stoking chute, and a pair of cleanout doors in the outside walls near their 90 middles. 95

100 FRANK PFEIFER.
